UNITED STATES PATENT OFFICE

ROLLA C. HARBORD, OF SPOKANE, WASHINGTON, ASSIGNOR OF ONE-THIRD TO HERMAN GEST, AND ONE-THIRD TO JAMES H. TRIMBLE, BOTH OF SPOKANE, WASHINGTON

MOTOR-VEHICLE SEMAPHORE

Application filed December 4, 1928. Serial No. 323,655.

My invention relates to motor-vehicle semaphores and the primary objects of the invention are to provide a comparatively simple semaphore having a signal hand normally housed within a cabinet and with means whereby the hand is moved to indicate the several directions in which the vehicle is going. Other objects are to provide means for simultaneously opening and closing the cabinet door in combination with the means for operating the hand. Further objects are to provide electrical contact means for simultaneously illuminating the hand in combination with the movements of the door and hand.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a general outline view in elevation showing the several positions of the signal hand;

Fig. 2 is a view in elevation of the device as a whole with the cabinet door open and its front cover removed;

Fig. 3 is a view in transverse section taken substantially on a broken line 3, 3 of Fig. 2 and showing the electrical contact means for illuminating the hand;

Fig. 4 is a detail view in perspective of the slotted connecting plate; and

Fig. 5 is a view in transverse section taken on a broken line 5, 5 of Fig. 1 and showing the hand in the extended position.

Referring to the drawings throughout which like reference numerals designate like parts, the numeral 5 indicates a hand lever arranged for manual operation and pivoted at 6 to an indicator plate 7 which may be secured to an instrument board 8 or other convenient place in the forward part of a motor-vehicle. A finger 9 extending from said lever is arranged so that its deflected point will register with slots 10, 11, 12 and 13 in said plate for reasons hereinafter set forth.

Another finger 14 extending from the lever

5 on the underside of the plate 7 has a cable 15 secured to the end thereof in any desired manner. Said cable is flexible and may have its deflected or bent portions enclosed by a casing 16 for protection and also for the purpose of strengthening its rigidity of alignment particularly when a pushing strain is exerted thereon as will be understood.

The cable 15 and its casing 16 extend through one end of a cabinet 17 with said casing secured at 18 to the bottom thereof and in longitudinal disposition therewith. Said cabinet may be mounted on any convenient and desired part of the vehicle 19 in a forward position where it will be visible for all the purposes for which it is intended. The cabinet is provided with a front cover 20 and a side door 21 hinged thereto at 22.

In Fig. 2 of the drawings the cover member 20 is removed for purposes of illustration. The remote end of the cable 15 is secured to the lower end 23 of a connecting plate 24 which is retained in slidable position by guide lugs 25. A link 26 is pivoted at 27 to an end of the connecting plate and is provided with an adjustment slot 28. Said link is pivoted at 29 to a projection on a collar 30 which is keyed to a sleeve 31 that is journalled on an axle 32 secured to the cabinet 17 and its front cover 20 as clearly shown in Fig. 5 of the drawings.

The hub 33 of an arm 34 is keyed or otherwise fixed to the sleeve 31. Said arm comprises two metal parts secured together by a bolt 35 and a hollow hand 36 rigidly secured to said arm at 37 is preferably made of translucent white material and provided with a colored spot 38, preferably red, that is painted or otherwise fixed on its forward interior portion. It will now be obvious that said hand may be swung by the foregoing described connecting parts to the different pivotal positions shown in Fig. 1.

As a means for opening and closing the door 21 synchronously with the movements of the hand 36 I have pivotally secured to said door a link 39 that is pivoted at 40 to a bell crank 41 which is pivoted to the cabinet 17 at 42. Said bell crank carries a pin 43 which slides in a slot 44 of the plate 24 and

the lower end portion 45 is deflected at right angles as clearly shown in Figs. 2 and 4 of the drawings.

In the position shown in full lines in Fig. 2 the pin 43 will be exactly at the junction point between the slot 44 and its deflected portion 45 and the door will be in the open position. In this position the finger 9 is in registration with the slot 11 and the hand 36 is in horizontal position indicating the signal "right turn". By moving said finger to slot 12 said hand will be moved down to the slanting position indicating "stop" while at the same time said pin will move to the remote end of the deflected slot portion and the door will continue to remain open.

Now by moving the finger 9 to the slot 13 the hand 36 will assume its full retracted position within the cabinet 17 as shown in dotted lines. Simultaneously the upward movement of the plate 24 and its deflected slot portion 45 will pivotally move the pin 43 and its bell crank 41 to the position shown in dotted lines in Fig. 2. Thus the bell crank 25 in its pivotal movement about the point 42 will draw the link 39 inwardly and close the door.

It is believed that the reverse movement back to the position shown in full lines in Figs 1 and 2 will be readily understood without a description in detail. In the raised position shown in dotted lines in Fig. 1 and indicating "left turn" the finger 9 is moved to the slot 10 and the pin 43 slides freely in the slot 44 as the plate 24 moves downwardly and therefore has no effect on the position of the door which will remain open.

My means for illuminating the hand 36 comprises a contact plate 46 insulatively secured to the connecting plate 24 and arranged to engage between a pair of spring fingers 47 mounted within the cabinet 17. A wire 48 leads from said spring fingers to the source of current and a wire 49 grounded on the metal cabinet leads from the contact plate to a lamp 50 mounted within the hand. When the door 21 is closed and the hand is in the retracted position said contact plate will be out of engagement with said spring fingers as shown in dotted lines in Fig. 2 and in engagement with a stop member 51 and the light will be out as will be understood.

It will now be apparent that I have provided a semaphore that is comparatively simple in construction, that is compactly housed within a cabinet, which embodies means for opening and closing the cabinet door and displaying the signal hand in all positions necessary for indicating the movements of the vehicle in which it is installed, and means for illuminating the signal hand simultaneously with its movements and the movements of the door.

Having thus described my invention, it being understood that minor changes in its con-

struction may be resorted to in its construction without departing from its scope and spirit, what I claim and desire to secure by Letters Patent of the United States is:—

1. A motor-vehicle semaphore comprising a cabinet, a hinged door, a signal arm normally housed within the cabinet when the door is closed, means for swinging the arm to displayed position comprising a hand lever, a flexible cable for the lever, a slidable connecting plate for the cable, a link plate pivoted to the connecting plate, and an arm projecting from the inner pivoted end of the signal arm pivotally connected to the link plate. 70

2. A motor-vehicle semaphore comprising a cabinet, a hinged door, a signal arm normally housed within the cabinet when the door is closed, means for swinging the arm to displayed position comprising a hand lever, a flexible cable for the lever, a slidable connecting plate for the cable, a link plate pivoted to the connecting plate, an arm projecting from the inner pivoted end of the signal arm pivotally connected to the link plate, means for opening and closing the door synchronously with the movements of the signal arm comprising a link arm pivoted to the door, a bell crank pivoted to said link and to the cabinet, a pin for said bell crank slidably disposed in a slot in the slidable connecting plate, and said slot having a right angular lower end portion wherein said pin receives when the slidable connecting plate is moved upwardly to retract the signal arm 90 and close the door. 95

In testimony whereof I affix my signature.
ROLLA C. HARBORD.
